TUBULAR CONSTRUCTION TOY

Harold P. Hubbard, Encinitas, Calif.

Application July 29, 1949, Serial No. 107,507

8 Claims. (Cl. 46—17)

1

My invention relates to a toy construction means, more particularly for use in constructing various toys which simulate various mechanical vehicles, or the like, and the objects of my invention are:

First, to provide a toy construction means of this class which is adapted to contribute greatly to the mechanical education of various persons, and particularly children;

Second, to provide a toy construction means of this class having tubular members of varying diameter, provided with holes and set screws therein, which may be used to construct a surprisingly great variety of mechanical devices, such as wheels, gears, cranks, links and other motion-transmitting mechanisms;

Third, to provide a toy construction means of this class which is particularly adapted for use in producing scale models of certain carnival entertainment devices and transportation equipment or the like;

Fourth, to provide a toy construction means of this class in which tubular members of a certain diameter are provided with spaced holes alternately extending therethrough transversely related to each other, whereby smaller tubular members may be readily inserted through said holes in angular relationship to each other, providing flexibility or versatility in the use of the mechanism for constructing various models of different vehicles or machines;

Fifth, to provide a toy construction means of this class which promotes the construction of very rigid and reliable models adapted to operate without undue maintenance attention; and

Sixth, to provide a toy construction means of this class which is very simple and economical of construction, efficient in operation, and which will not readily deteriorate or get out of order.

With these and other objects in view, as will appear hereinafter, my invention consists of certain novel features of construction, combination and arrangement of parts and portions, as will be hereinafter set forth in detail and particularly described in the appended claims, reference being had to the accompanying drawings and to the characters of reference thereon, forming a part of this application, in which:

Fig. 1 is a fragmentary side elevational view of a toy assembled from various parts of my toy construction means, and Fig. 2 is an enlarged fragmentary sectional view, taken from the line 2—2 of Fig. 1.

Similar characters of reference refer to similar parts and portions throughout the several views of the drawings.

2 The frame members 1, 2, 3 and 4, axle 5, wheel tire 6, wheel rim 7, wheel spokes 8, 9 and 10, wheel rim supports 11, 12, 13, 14, 15 and 16, crank arms 17 and 18, links 19, pin gears 20 and 21, and the gear axles 22 and 23, constitute the principal parts and portions of my toy construction means.

The frame members 1 and 2, shown in Fig. 1 of the drawings, are similar in construction, and are each usable for the construction of a large 10 variety of framework and mechanism, as desired. The frame member 1 is a hollow tubular member, provided with holes 1b extending therethrough on a substantially horizontal plane and spaced relative to each other. This frame member 1 is also provided with a plurality of holes 1c, which are axially disposed at substantially ninety degrees to the axis of the holes 1b and placed intermediate the holes 1b extending through the frame member 1.

20 The vertically disposed frame members 3 and 4 extend through corresponding openings in the horizontal frame members 1 and 2 similar to the openings 1c hereinbefore described. These frame members 3 and 4 are engaged at their opposite ends by means of set screws 1a and 2a, which are screw-threaded in the side walls of the frame members 1 and 2, as shown in detail in Fig. 2 of the drawings. It will be noted that the frame member 3, as shown in Fig. 2 of the drawings, is provided with holes 3a therein, which said screws 1a and 2a engage for rigidly connecting the frame members 1 and 2 with the frame members 3 and 4.

25 It is to be noted, however, that the screws 1a and 2a may engage the outer side of the frame members 3 and 4 in the conventional manner of set screws and need not be extended into the holes 3a in the event intermediate positioning of the frame members 1 and 2 is desired at a location between the holes 3a longitudinally of the frame member 3 or corresponding openings in the frame member 4.

30 The frame member 1, intermediate the openings 1b therein, and intermediate the openings 1c, is provided with a plurality of tapped holes 1e, in which the screws 1a may be internally threaded for engagement with various tubular members, such as the frame members 3 and 4 for securing the same in rigid relationship with the frame member 1, as desired. It is to be here noted 35 that the frame members 2, 3 and 4 are provided with similar tapped holes, to be employed as set screw holes for securing various parts and mechanisms thereto.

35 The wheel tire 6 is a resilient band-shaped member, fitted around the wheel rim 7, which is an elongated piece of sheet metal, overlapped

at its ends 7a and 7b, which provides certain diametric adjustment of the rim supports 11 on the wheel spokes 8, 9 and 10. The wheel spoke 8 is a hollow tubular member, fixed on the axle 5 by means of the set screw 5a, and extending laterally through the spoke 8 are the spokes 9 and 10, held in place by screws 9a and 10a. Opposite ends of each of the wheel spokes 8, 9 and 10 extend into close proximity to the wheel rim 7 and supported thereon are the rim supports 11 to 16, inclusive, which are tubular members of slightly larger diameter, through which the wheel spokes 8, 9 and 10 extend. These rim supports 11 to 16, inclusive, are provided with set screws for fixing the same on the wheel spokes 8, 9 and 10, providing adjustable supports for the wheel rim 7, surrounded by the resilient wheel tire 6. The axle 5 is extended through the lower end of the axle supports 5b, which are secured to the lower frame member 2 by means of a set screw common to the frame member 2, as hereinbefore described.

The crank arm 17 is fixed to the axle 5 by means of the set screw 17a and pivotally secured to the crank arm 17 near its one end by means of the screw 19a is the link 19, which is pivotally secured at its opposite end by means of the screw 18a to the crank arm 18, which is fixed to the gear axle 22. The central spoke 21a of the pin gear 21 is fitted over the axle 22, and secured thereon by means of a conventional set screw similar to the screw 5a hereinbefore described.

The pin gear 21 is provided with spokes 21b and 21c, parallel to the spoke 21a, through which the lateral spokes 21d, 21e, 21f and 21g extend. On the outer ends of all of the spokes of the pin gear 21 are hollow tubular gear pin members, substantially larger in diameter than the hereinbefore mentioned spokes of the gear 21, all of which are secured thereon by set screws. It is to be noted that the spokes of the gear 21 are adjustable and fixed together by means of set screws for supporting the pin gear members 21h in certain spaced relationship to each other in an arcuate row. The pin gear members 21h are engageable with the pin gear members 20a, which are fitted to the spokes 20b, 20c and 20d by set screws, all as shown in Fig. 1 of the drawings. The gear spoke 20c is fixed to the gear axle 23, which is revolvably mounted and extended through the frame member 1.

It is to be noted that Fig. 1 of the drawings is a side elevational view of a toy, and that the toy includes two wheels, one on each side, and a pair of the frame members 1 and a pair of the frame members 2, so that opposite ends of the gear axles 22 and 23 are supported at opposite sides of the frame composed of the secondary frame members 1 and 2, and the axle 5 is also supported at its opposite ends adjacent the two wheels, each composed of a tire 6, rim 7, and supporting spokes, 8, 9 and 10. Pivoted to the forward end of the frame members 2 is a drawbar 24, which may be used in towing the toy, as shown in Fig. 1 of the drawings.

The operation of the toy constructed of my toy construction means as shown in Fig. 1 of the drawings is substantially as follows:

When the toy is towed by the drawbar 24, the tires 6, bearing on the horizontal surface, cause the supporting wheels to rotate, which turns the crank arm 17, actuating the links 19,

which rotates the axle 22 by means of the crank arm 18, causing the rotation of the pin gear 21 and rotational engagement of the pin gear 20 therewith.

5 In general, in the operation of my toy construction means, various models and types of toys may be made, which simulate various machines and vehicles or the like. Construction of toys employing my toy construction means affords educational experiences for children and grown-ups, and provides various toys of very durable character.

Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

Having thus described my invention, what I claim as new and desire to secure by Letters Patent is:

1. In a toy construction means, pin gears, including a plurality of tubular spokes, some of said tubular spokes extending transversely through the other tubular spokes, and tubular gear pins on the extending ends of said spokes, arranged in an arcuate row, having their axes transversely of said spokes.

2. In a toy construction means, a wheel, comprising a resilient tire, a sheet metal rim having its opposite ends overlapped relative to each other internally of said resilient tire, rim supporting members of tubular form engaging the inner side of said rim, and tubular spokes supporting said rim-supporting members at their opposite ends, some of said spokes extending transversely through other of said spokes.

3. In a toy construction means, a wheel, comprising a resilient tire, a sheet metal rim having its opposite ends overlapped relative to each other internally of said resilient tire, rim supporting members of tubular form engaging the inner side of said rim, and tubular spokes supporting said rim-supporting members at their opposite ends, some of said spokes extending transversely through other of said spokes, a middle spoke having an axle opening therein, and an axle extending therethrough.

4. In a toy construction means, a pin gear including a plurality of tubular spokes, some of said spokes extending transversely through another spoke, and tubular gear pins on the extending ends of said spokes, said gear pins being arranged in an arcuate row and having their axis transversely of said spokes.

5. In a toy construction means, a pin gear including a diametrically positioned spoke, other spokes extending transversely through said diametrical spoke, and tubular gear pins on the extending ends of said spokes, said gear pins being arranged in an arcuate row and having their axis transversely of said spokes.

6. In a toy construction means, a wheel comprising a circular rim, rim supporting members of tubular form engaging the inner side of said rim, and tubular spokes having opposite ends supporting said members, some of said spokes extending transversely through another spoke.

7. In a toy construction means, a wheel comprising a circular rim, a tubular rim supporting member having cylindrical sides, engaging the

inner side of said rim, and spokes having opposite ends entering and supporting said member, some of said spokes extending transversely through another spoke.

8. In a toy construction set, a wheel comprising a circular rim, rim supporting members engaging the inner side of said rim, tubular spokes having opposite ends supporting said members, one of said spokes extending diagonally with respect to said rim, other spokes extending 10 transversely through said diagonal spoke, an axle extending through and affixed to said diagonal spoke, a tubular crank arm affixed to said axle, and a tubular link rotatably connected to said crank arm.

HAROLD P. HUBBARD.
